[57] CLAIM

The ornamental design for a telephone handset, as shown and described.

DESCRIPTION

FIG. 1 is a front, top and right side perspective view of a telephone handset showing my new design;
FIG. 2 is a front elevational view thereof;
FIG. 3 is a side elevational view thereof, the side opposite being a mirror image;
FIG. 4 is a rear elevational view thereof; and
FIGS. 5 and 6 are respectively end views thereof, and the view of the end opposite to it.
